INVENTOR:

Eduard Reed by his attorney
Hartel & Co.

United States Patent Office.

EDEN REED, OF ST. LOUIS, MISSOURI, ASSIGNOR TO HIMSELF AND LEWIS L. WARREN, OF SAME PLACE.

Letters Patent No. 102,864, dated May 10, 1870.

IMPROVEMENT IN ALARM-TILLS.

The Schedule referred to in these Letters Patent and making part of the same.

To all whom it may concern:

Be it known that I, EDEN REED, of St. Louis, in the county of St. Louis and State of Missouri, have made certain new and useful Improvements in Alarm-Tills; and I do hereby declare that the following is a full and true description thereof, reference being had to the accompanying drawings, and to the letters of reference marked thereon.

This invention relates to the arrangement of the tumblers, operating levers, and detent for retaining the tumblers until properly raised in a locking device for a money-drawer or till, to furnish a safely-closed receptacle for valuables, and said locking device to be, furthermore, in connection with an alarm device which shall indicate any attempted not authorized opening of the till-drawer.

To enable those herein skilled to make and use my said invention, I will now more fully describe the same.

Figure 1 is a bottom plan of the lid of the till, which is usually a counter or shelving top-board.

Figure 2 is a sectional elevation of the till and its attachments.

Figure 3 is an elevation of the front end of the drawer, showing the metallic detent, and

Figure 4 is a horizontal section, showing the key-bars in plan view.

My said devices are applicable to various forms of drawers and similar receptacles. The more usual application to the ordinary money-drawers under tables or counters is illustrated in the figures.

The drawer A slides in or out so as to be covered or accessible, as desired, under the cover-board B.

The front (usually vertical) drawer-board A' is made of strong material, so as to contain the keys C, of which there may be any number required for any desired number of combinations in opening; said keys are stout metallic bars, standing vertically. The keys have their heads c cut to present the projections c', which are at the edges of the head surfaces.

Within the board A' is the detent-plate D, having the wide opening d, and proper guiding-edges d'; the plate is firmly secured to the board A'.

On the under side of the cover-board B is a guide-plate, E, which guides the tumblers F in their horizontal play. The number of tumblers corresponds to the number of keys, and a rock-shaft, f, passing through the rear ends of the tumblers, connects all of them with the spring G.

The rock-shaft f is immediately under a rod, g, which has a projection g'.

The rod g, as well as the spring G, is connected with the striker H, the arm of which is pivoted at h, and which sounds the alarm on the bell I.

It is plain that the action of the spring G is to draw the tumblers F back to limit this play. The plate E has a slot, e, against the edge of which one or more tumblers impinges, by a suitable stop, f'. The stop f', at the rear of the tumblers, impinging against the rear edge of the plate E, limits the play in the other directions.

The tumblers F have arrow-shaped heads. The heads f' drop beyond the detent-plate D, thus locking the drawers.

If, now, the attempt is made to open the same wrongfully, then the drawer will move forward slightly, drawing the tumblers F out, until the rock-shaft f, in its radial movement, is compelled to leave the projection g', whereupon the spring G causes the alarm to sound.

In opening the drawer properly the keys C, by their projections c, will raise the tumblers, but such keys must be operated together whose projections stand beyond the thickest parts of the arrow-heads f' of the tumblers, as those keys which stand reversed, or so that their projections c' are next to the detent-plate D, will prevent the tumblers above them from dropping to a lock.

The devices thus arranged are simple and efficient, and their economical construction and durability gives them advantages over many more costly devices.

Having thus fully described my invention,

What I claim is—

1. The combination of the tumblers F, the rock shaft f, rod g, projection g', the spring G, and alarm device H I, substantially as and for the purpose set forth.

2. The combination of the detent D, tumblers F, f', and keys C c', operating and arranged substantially as set forth.

In testimony of said invention I have hereunto set my hand in the presence of—

EDEN REED.
